A photograph of a reel-to-reel motion picture projector. The projector is mounted on a wooden base. It has a large cylindrical reel at the bottom, a smaller reel at the top, and a lens at the front. The projector is connected to a power source by a cord.

UNITED STATES PATENT OFFICE

FREEMAN H. OWENS, OF NEW YORK, N. Y., ASSIGNOR TO OWENS DEVELOPMENT CORPORATION, OF NEW YORK, N. Y., A CORPORATION OF NEW YORK

PHOTOGRAPHIC SOUND RECORDING AND REPRODUCING APPARATUS

Application filed February 18, 1930. Serial No. 429,322.

This invention relates to improvements in photographic sound recording and reproducing apparatus, the principal object of the invention being to provide an apparatus which may be used either as a recording or a reproducing machine and which apparatus is compact and inexpensive and at the same time very efficient in use both for recording and reproducing photographic sound records.

The invention is particularly adaptable for sound recording and reproducing apparatus which may be used in the home or by amateurs, and is therefore portable.

Other objects and advantages of the invention will appear as the description proceeds.

In the drawings accompanying this specification,

Figure 1 is a side view of an apparatus embodying the features of the invention, the lid of the main housing being shown open and broken away and a part of the lamp housing also broken away;

Figure 2 is a side elevation showing the side of the machine opposite from Figure 1, the side wall of the main housing being removed to show the arrangement of the elements within said housing; and

Figure 3 is a sectional plan view of the apparatus.

Referring to the drawings, 1 designates the main housing of the apparatus, said housing being provided with a hinged lid 2 and carrying a film magazine 3 preferably disposed in the position shown in the drawings, that is to say, the magazine extends across one corner of the housing and carries the usual film supply and takeup reels, one side wall of the magazine forming a cover or lid hinged at 4 to afford ready access to the interior thereof. The housing or casing carries also the usual sprocket 5 and film retaining rollers 6 for feeding a film 7 from the supply reel *a* to the camera housing and back to the takeup reel *b* in the magazine.

A motor 8 is mounted in the housing 1, said motor carrying on its shaft a pulley 9 which transmits motion by means of a belt 10 to a pulley 11 mounted for rotation on a shaft 12, which shaft in turn is mounted for rotation in the walls of the housing 1 and has

secured thereto a flywheel 13. The pulley 11 has an elongated hub 14 provided with a clutch disk 15 having pins 16 adapted to engage openings in the flywheel and thereby cause rotation of the shaft 12 with the pulley 11, 55 said pulley and its clutch disk being slidable on the shaft into and out of engagement with the flywheel. Disposed in the housing 1 is a second shaft 17 mounted for rotation in a pair of brackets 18 secured to one of the side walls 60 of the housing, said shaft extending tangentially of the shaft 12 and in a direction inclined to the horizontal. Secured on the shaft 12 at the point where it intersects shaft 17 is a worm 19 in mesh with a worm gear 20 65 on said shaft 17, which latter shaft has secured thereon near its opposite end a worm 21 in mesh with a worm gear 22 secured on the shaft of the sprocket 5. Motion is thus imparted from the motor 8 to the sprocket 70 5 whereby the latter is rotated to draw the film from the supply reel and pass it on to the takeup reel. The takeup reel is rotated to take up the film by means of a belt 23 passing over pulleys 24 and 25, secured respectively 75 on the pintle of the takeup reel and the shaft of sprocket 5.

The shaft 17 is provided with a fly ball governor 26 for regulating the speed of rotation of said shaft, said governor having secured thereto a disk 27 adapted to contact with a brake arm 28 pivoted on the wall of the housing 1. The brake arm may be adjusted to contact sooner or later with said disk 27, by means of a rod 29 swiveled at its inner end 85 in the brake arm 28 and threaded adjacent to its outer end in the wall of the housing, said rod being provided outside of the housing with a knurled head or knob 30 for manually rotating the rod. A coil spring 31 secured at one end to the wall of the housing and at its opposite end to the brake arm 28 serves to maintain said arm under tension.

Within the housing 1 is disposed a second housing 32 in the path of the film 7 as it passes from the sprocket 5, the front end of which housing is curved to permit the film to pass in smooth contact therewith, said end being provided with an opening 32a to permit passage of light through the film as it passes over the

end of the housing. A pivoted gate forming member 33 is mounted in position to retain the film in proper contact with the end of the housing. On the shaft 12 is mounted a second sprocket 34 adapted to pull the film through said gate and deliver it to the takeup reel, a suitable clamping roller 35 carried by a pivoted arm 36 being adapted to maintain the film in engagement with said sprocket. 5
10 Mounted in the housing 32 is a photoelectric cell 37 with its window in position to receive light rays after their passage through the film to the interior of the housing 32.

Extended forward from the housing 1 and 15 in alignment with the interior housing 32 is a housing 38 in which is mounted the usual optical slit system commonly used in the recording and or reproduction of photographic sound records, said housing terminating in a lamp housing 39 in which is mounted a lamp 40 in alignment with the optical system and with the opening in the end of the housing 32. It will be understood, of course, that for reproducing purposes the output of the photo- 20 electric cell will be connected to an amplifier and loud speaker and the lamp 40 with a microphone in the usual manner. These devices are so well known in the art that they are omitted from the drawings for the sake 25 of clearness. The optical slit system may consist of condenser lenses 38a, slit 38b, and focusing lens 38c for focusing the illuminated areal image of the slit upon the film 7.

The operation of the apparatus is as follows:—If it is desired to make a sound record, a supply reel carrying a sensitized film is placed in position in the section A of the magazine, and the film threaded over the sprocket 5, the front wall of the housing 32, 30 behind sprocket 34 and between said sprocket and the roller 35, thence back to sprocket 5 and to a takeup roller mounted in section B of the magazine, as clearly shown in Figure 1. Between the roller 35 and the sprocket 5, a 35 sufficient length of film is left to maintain a loop at this point thereby to avoid strain on the film when being returned to the magazine by the sprocket 5. With the film so threaded, the speaker or singer takes his or her position at the microphone and the motor is 40 started. The sounds to be recorded are picked up by the microphone and translated into electrical impulses which may operate to vary the intensity of the lamp 40, the varying 45 illuminated image of the slit 38b being focused by the optical system on the film as it passes over the end of the housing 32 thereby producing the desired record. It will be 50 understood of course that other types of 55 sound recording means may be used. At the same time, if the slit in the end of housing 32 is left open during the recording, the light rays modulated by the variations of the intensity of the lamp will pass through said slit 60 and be caught by the photoelectric cell, which 65

will deliver said modulated rays in the form of electrical impulses to the amplifier and speaker. It will thus be seen that by listening in at the speaker while the record is being recorded a check can be made of the quality 70 of the record.

When the apparatus is to be used for reproducing, the only changes necessary are as follows: Instead of a sensitized film, a film bearing a sound record is threaded through the apparatus as above described, and the microphone is cut out. The lamp 40 thus maintains a constant intensity and the light rays are caught by the photoelectric cell after they have been modulated by passing through the sound record carried by the film, such modulated light rays being translated by the photoelectric cell into electrical impulses, which are then amplified and made audible in the usual manner. 75

I claim:

1. A sound recording and reproducing apparatus, comprising in combination, a housing, a film magazine forming an integral part of said housing and having a supply reel and a takeup reel mounted for rotation, a hollow member disposed within said housing and having a curved and slit end wall, means for conducting a film from said supply reel, over said curved end wall and to the takeup reel, 90 movable means for maintaining the film in contact with said wall, means for projecting light rays on said film as it passes over said wall, a photoelectric cell disposed in said hollow member in position to receive the projected light rays after their passage through the film, and means for varying the intensity of the light rays before their passage through the film. 95
100

2. A sound recording and reproducing apparatus, comprising in combination, a main housing, a film magazine forming an integral part of said housing and having a supply reel and a takeup reel mounted for rotation, an inner housing disposed within said main housing and having a curved slit end, a photoelectric cell mounted in said inner housing with its window adjacent to said slit end, means for conducting a film from said supply reel to said takeup reel and including means for 105 causing the film to pass in contact with the slit end of the inner housing, a lens housing in alignment with said inner housing, and a light source in communication with said lens housing and in alignment with said inner 110 housing. 115
